REFILLABLE PENCIL

Horace J. Alter, Brooklyn, N. Y.

Application September 16, 1936, Serial No. 101,150

3 Claims. (Cl. 120—21)

This invention relates to refillable draftsman's or artist's pencils and has for the primary object the provision of a device of this character wherein the body thereof is approximately the same length as that of an ordinary pencil and has a portion preferably of hexagonal shape to permit the body to be readily grasped for use and is located adjacent the writing end of the body while the remaining portion of the body tapers and is of cylindrical shape so that when the pencil is in use a low center of gravity will be had and adjacent the writing end, which so balances a pencil as to relieve holding strains.

Another object of the invention is the provision of a holding receptacle secured to the non-writing end of the body for removably attaching to said body a draftsman's prick point, either end of which may be easily brought into position for use while the other end is fully protected.

A further object of this invention is the provision of an improved chuck carried by the body wherein the lead will be engaged and gripped over a larger portion thereof than heretofore possible in similarly constructed pencils to prevent highly localized stress on the lead.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a refillable pencil constructed in accordance with my invention.

Figure 2 is a vertical sectional view illustrating the same.

Figure 3 is a fragmentary vertical sectional view showing the prick point holder secured to the body with the point in operative position.

Figure 4 is a sectional view taken on the line 4—4 of Figure 2.

Figure 5 is a fragmentary vertical sectional view illustrating a modified form of my invention.

Referring in detail to the drawing, the numeral 1 indicates the body of the pencil having a bore 2 and is constructed from some suitable composition of material. The body 1 adjacent the writing end of the pencil is preferably of hexagonal shape, as shown at 3, to permit the body to be readily grasped and the body from the hexagonal shape towards the non-writing end tapers and is of cylindrical shape and has its end recessed

to receive a receptacle 4 of substantially tubular shape having a flange 5 to abut the end of the body. The receptacle 4 is employed to receive a draftsman's prick point 6 either end of which may be confined within the receptacle or holder while the other end is exposed for use. While the receptacle 4 is shown and described as being fitted in the recessed end of the body 1 it is to be understood that the receptacle by increasing the size of the bore at one end may be fitted over the end of the body.

The hexagonal end 3 of the body besides providing an efficient grip for the body also provides a low center of gravity to the pencil in entirety, that is, bringing the center of gravity closer to the writing end of the pencil whereby the pencil may be more easily balanced when in use. The hexagonal-shaped end of the body is recessed and internally threaded to receive an exteriorly threaded stud or plug 8 which has threaded thereon a retainer nut or sleeve 9. The sleeve or nut 9 has threaded therein a chuck 10 including an outer tapered portion 11 threaded to the nut or sleeve 9 and contacting a reduced extension 12 formed on the stud or plug 8. Operating within the outer tapered portion 11 are elongated jaws 13 preferably three in number which engage with a lead 14 for a substantial distance, the lead extending into the bore 2 by way of a bore 15 formed in the stud 8. The jaws taper towards their free ends to correspond with the taper of the outer tapered portion 11 of the chuck so that said jaws will evenly contact with the lead substantially throughout their entire length. This construction of chuck provides maximum contact of the chuck with the lead and eliminates highly localized stress on the lead, consequently reducing the chances of breaking the lead to a minimum still efficiently securing the lead against slippage.

Colored bands 16 may be applied to the body to denote different grades of lead, permitting a person at a glance to determine what grade of lead is in the pencil regardless of the position of the pencil.

Referring to the modified form of invention the hexagonal end 3 of the body 1 has formed thereon a reduced extension 17 tapered, as shown at 18, and has the bore 15 extending therethrough. A retaining nut or sleeve 19 is threaded on the extension and has an inner annular shoulder 20. A chuck 21 is threaded into the nut or sleeve 19 and includes the tapered jaws 22, the inner ends of which are shouldered, as shown at 23, to ride on the shoulder 20 and be located

adjacent the end of the reduced extension 17. The outer ends of the jaws are internally knurled, as shown at 24. The chuck 21 includes the outer tapered sleeve-like portion 25 for effecting operation of the jaws into gripping the lead.

Having described the invention, I claim:

1. A refillable pencil comprising a body having a bore, a stud having a bore carried by said body, said bores adapted to receive a lead, a retaining nut threaded on said stud, a chuck sleeve threaded into said nut, elongated tapered jaws arranged in the sleeve to grip the lead.
2. A refillable pencil comprising a body having a bore, a stud having a bore threaded to said body, said bores adapted to receive a lead, a retaining nut threaded on said stud, a chuck sleeve

threaded into said nut, elongated tapered jaws arranged in the sleeve to grip the lead, an extension formed on the stud to abut the jaws, and a shoulder formed in the chuck sleeve and engaging the extension.

3. A refillable pencil comprising a body having a bore and provided with a reduced screw threaded end with the bore extending therethrough to receive a lead, a retaining nut threaded on the extension, and an internal shoulder formed in the nut, a chuck sleeve threaded in the nut, elongated tapering jaws arranged in the sleeve to engage with the lead and having shouldered ends engaging with said first shoulder.
